UNITED STATES PATENT OFFICE.

FRANK JOSEPH SCHWARTZ, OF VILLA GROVE, ILLINOIS.

WEATHER-STRIP.

No 839,213.

Specification of Letters Patent.

Patented Dec. 25, 1906.

Application filed May 8, 1906. Serial No. 315,806.

To all whom it may concern:

Be it known that I, FRANK JOSEPH SCHWARTZ, a citizen of the United States, residing at Villa Grove, in the county of Douglas and State of Illinois, have invented a new and useful Weather-Strip, of which the following is a specification.

This invention relates to improvements in automatic weather-strips for attachment to doors, more particularly outside doors, and associated with the sills or thresholds, and has for its object to provide a simply-constructed device of this character which may be readily applied to any size or form of door and operates effectually to exclude cold, rain, or snow.

With these and other objects in view, which will appear as the nature of the invention is better understood, the invention consists in certain novel features of construction, as hereinafter fully described and claimed.

In the accompanying drawings, forming a part of this specification, and in which corresponding parts are denoted by like designating characters, is illustrated the preferred form of the embodiment of the invention capable of carrying the same into practical operation.

In the drawings, Figure 1 is a side elevation, partly in section, of a portion of a door and its frame and threshold with the improved device applied. Fig. 2 is a section on the line 2 2 of Fig. 1. Fig. 3 is a section on the line 3 3 of Fig. 1. Fig. 4 is a perspective view of one of the gap-closing keys detached.

The door to which the device is applied is indicated at 10, the jamb at 11, and the threshold at 12, of the usual construction. Formed in the bottom edge of the door is a channel 13, and movable in this channel is a weather-strip 14, preferably of metal. Embedded in the lower portion of the door and transversely of the channel 13 are two or more tubular members 15, having transverse recesses (indicated at 16) and corresponding to and in alinement with the channel 13, and thus bearing over the weather-strip 14. The weather-strip thus extends through the tubular members and is movable vertically within the recesses therein. The weather-strip extends for a short distance below the lower line of the door 10 and is provided with transverse pins 18, projecting through slots 17 in the tubular members. By this simple means the weather-strip 14 is free to move

vertically within the range of the slots, but is limited in its movement by the pins 18.

Disposed within the tubular members 15 are springs 19, bearing at one end upon the strip 14 and supported in position by a plug 20, inserted into the upper end of the tubular members. The tubular members are further secured by transverse screws or other suitable means, (represented at 21.) By this means the weather-strip is yieldably supported in its downward position.

Attached to the threshold 12 is a metal plate 22, preferably curved on its upper surface and with a yieldable strip 23, preferably of rubber, beneath one edge and projecting at the outer edge. A packing-strip 25, of rubber or the like, is embedded in the lower face of the door and bears against the strip 14 to prevent the entrance of rain or snow into the channel 13. By this arrangement when the door is closed the weather-strip 14 engages the metal plate 22 and rides over it, the plate yielding and becoming seated when the door is in closed position against the projecting portion of the yieldable member 23, as shown in Fig. 2, and effectually excluding all cold air and moisture from the different sources.

The springs 19 will be of sufficient strength to maintain the weather-strip in closed position, but will yield to the force required to open the door. Cover-plates 28 are attached to the door to form closures to the ends of the channel 13. Small wedge-shaped plates 26 27 are forced into the strip 12 and the jambs at each side to close the small gaps which would otherwise occur between the ends of the weather-strip and the jambs.

Having thus described the invention, what is claimed as new is—

1. In a device of the class described, the combination with a structure including a door and its frame and a threshold, said door having a channel in its lower end, of a plate attached to said threshold, a yieldable element between said threshold and plate, a weather-strip movably disposed within said channel and bearing upon said yielding element, and means for yieldably supporting said strip in position.

2. In a device of the class described, the combination with a structure including a door and its frame and a threshold, said door having a channel in its lower end, of a plate attached to said threshold, a yieldable ele-

ment between said threshold and plate at one edge and with a portion extending in advance of the plate, a weather-strip movably disposed within said channel and bearing upon said plate and against said extending portion and means for yieldably supporting said strip in position.

3. In a device of the class described, the combination with a structure including a door and its frame and threshold said door having a channel in its lower end, a weather-strip movably disposed within said channel,

means for yieldably supporting said strip in position and a flexible backing-strip attached to the door and bearing laterally against said weather-strip. 15

In testimony that I claim the foregoing as my own I have hereto affixed my signature in the presence of two witnesses.

FRANK JOSEPH SCHWARTZ.
